UNITED STATES PATENT OFFICE

SPENCER FANNIN, OF FLINT, MICHIGAN.

KEY HOLDER.

Application filed February 1, 1923. Serial No. 616,417.

To all whom it may concern:

Be it known that I, SPENCER FANNIN, a citizen of the United States, residing at Flint, in the county of Genesee and State of Michigan, have invented certain new and useful Improvements in Key Holders, of which the following is a specification.

My invention relates to a door key holder.

The object is to provide a device which will prevent the key from being pushed out 10 of the lock outside the door.

Another object is to provide a simple little device of this character that can be easily carried around and applied to a door key when desired or removed with equal facility therefrom, after having been applied. It is so constructed that it may be left in place even while the key is turned and until the key is actually to be removed 20 from the inside of the door by the person or proper authority.

In the accompanying drawings:

Figure 1 is a view in perspective showing the key held in position in the keyhole of a 25 door-lock with the key in position, part of which is shown in dotted lines;

Fig. 2 is a horizontal section through the holder;

Fig. 3 is a sectional view taken at right 30 angles and looking into the device; and,

Fig. 4 is a perspective view of one part of the device.

The entire keyholder is preferably made of two pieces of cheap metal.

The numeral 1 represents a ring and 2 is a tang integral with one edge of the ring and extending approximately in line with the axial center of the ring or in position to be inserted in the key-hole 3 of the lock 40 adjacent to the key K as illustrated in Fig. 1.

The other part of the holder is preferably made of a single piece of thin sheet metal folded at the center to form a guard 4 to receive the handle 5 of the key as shown in full lines in Fig. 1 and dotted lines in Fig. 2. This terminates in extending flanges 6 and 7 which fit in the circumference of the ring and are capable of turning therein 50 when desired and these flanges terminate in lips 8 and 9 which embrace the inner surface of the ring while the inner ends of the shield 4 form shoulders 10 that embrace the opposite surface of the ring 1 midway between the lips and hold the two parts of the device rotatably together.

From opposite sides of the shield 4, spring catches are cut and formed, the catch 11 is to slide over the handle of the key and spring into it and hold it against removal 60 from the key-holder until an authorized person lifts this catch.

The other catch 12 extends in the other direction and its free end lies in the notch 13 in the lip 9 in position to enter the notch 14 in the ring 1 when the key is in position, as indicated in dotted lines in Figs. 1 and 2, to hold the key against turning.

Thus in a simple way I have provided means for absolutely precluding a burglar or 70 unauthorized person from either poking the key out of the key-hole or turning it from the outside, while at the same time providing a simple little device that can be carried about in the pocket and applied to any door 75 key.

It is understood that the key can be turned from the inside without removing the holder by simply pushing the catch 12 out of the notch 14 and turning it with the key just 80 as the key would be turned without it. The catch 12 automatically springs back into the notch 14 on being turned to lock the door, so that the device may be left upon the key until it is desired to remove the key from 85 the lock and it may be removed from the lock or rather the key of the lock by simply lifting the catch 11 away out of engagement with the handle of the key and removing the holder from the lock, or rather from the 90 key and key-hole.

It is understood that this key-holder is applicable to any lock having the ordinary key whether it be in a house, apartment, office, store or hotel and it only requires removal from the lock when the key is to be 95 removed but it may be left within reach of the lock or carried about.

I claim:

1. A key-holder made of two members connected together, one having means for receiving a key and holding it during the rotation thereof, and being rotatably connected with the other member and means for locking said key-receiving member against turning relative to the other. 100

2. A key-holder made of two members connected together, one having means for receiving a key and being rotatably connected with the other, and a spring attached to said 110 key-receiving member and engaging the other to prevent the rotation of the key.

3. A key-holder including a ring having a tang to be received in a keyhole, and a shield rotatably connected with the ring and having means for receiving a key, said rotatable shield being adapted to turn on an axis substantially coincident with the axis of the key.

4. A key-holder made of two parts sprung together and rotatably connected together, one having means to receive the end of the key and the other having means to prevent the key from being turned or removed from the lock from one side of the door or by the unauthorized, and means for locking one of said parts against turning with respect to the other part.

5. A key-holder made of two parts sprung together and rotatably connected together, one having means to receive the end of the key and the other having means to prevent the key from being turned or removed from the lock from one side of the door or by the unauthorized, and means for locking one of said parts against turning with respect to

the other part, one of said parts having a catch for fastening the key-holder to the key.

6. A key holder including a notched ring having a tang, a shield rotatably connected with the ring and having two catches, one to fasten the holder to the key and the other to lock the shield against turning with respect to the ring.

7. A key-holder including a notched ring having a tang, a shield rotatably connected with the ring and having two catches, one to fasten the holder to the key and the other to lock the shield against turning with respect to the ring, a shield having outwardly extending flanges each of which has a lip, and provided with shoulders, the latter to embrace one side of the ring and the lips the other side of the ring, one lip having a notch to receive and guide the spring catch which locks the shield against turning in the ring.

In testimony whereof I hereunto affix my signature.

SPENCER FANNIN.
